UNITED STATES PATENT OFFICE.

EMIL A. CHRISTOPH, OF CHICAGO, ILLINOIS, ASSIGNOR TO MCGILL MANUFACTURING COMPANY, A CORPORATION OF INDIANA.

BEATER.

1,010,019.

Specification of Letters Patent. Patented Nov. 28, 1911.

Application filed January 18, 1911. Serial No. 603,236.

To all whom it may concern:

Be it known that I, EMIL A. CHRISTOPH, a citizen of the United States, residing at Chicago, in the county of Cook and State 5 of Illinois, have invented a new and useful Improvement in Beaters, of which the following is a specification.

My invention relates more particularly to devices for beating eggs, cream, dough, and 10 the like, of the type involving a casing, a spring-pressed spiral rod carrying beater blades, and means on the casing engaging with the spiral portion of the rod for rotating the latter in opposite directions 15 when the casing is reciprocated on the rod; and my objects, generally stated, are to provide a simple construction of device of the character stated, which shall be economical of manufacture, highly useful for performing the work required of this class of devices, and which shall be so constructed as 20 to permit of the ready interchanging of blades suitable for beating different materials.

My invention is illustrated in the accompanying drawings, in which—

Figure 1 is a view in elevation of an egg-beater constructed in accordance with my invention. Fig. 2 is a plan view of the 30 blank from which the handle of the beater is formed. Fig. 3 is a view in elevation of the spiral rod carrying the beater-blades. Fig. 4 is a perspective view of a follower carried on the inner end of the beater-rod 35 and forming a stop for one end of the rod-driving spring. Fig. 5 is a broken view in sectional elevation of the upper end of the beater. Fig. 6 is a section taken at the line 6 on Fig. 5 and viewed in the direction 40 of the arrow. Fig. 7 is an enlarged section taken at the line 7 on Fig. 1 and viewed in the direction of the arrow. Figs. 8 and 9 are perspective views of the beater-blades employed. Fig. 10 a section taken at the 45 irregular line 10 on Fig. 7 and viewed in the direction of the arrow. Fig. 11 is a broken view in elevation and partly sectional, of the device of the preceding figures, showing a blade attached thereto, especially 50 adapted for beating cream. Fig. 12 is an edge view, in elevation, of the lower end of the beater-rod. Fig. 13 is an end view of the device of Fig. 11. Fig. 14 is a face view of a desirable construction of blade for

beating batter, and Fig. 15 an edge view of 55 the blade of Fig. 14.

Referring particularly to Figs. 1 to 10 inclusive, the handle of the device which is in the form of a casing is illustrated at 11 and is preferably formed from a sheet-metal 60 blank 12 which is of substantially rectangular shape and is provided at its opposite ends with circular extensions 13 each formed with a projection 14. The handle is formed by bending the blank 12 to tubular form 65 in which its free edges overlap each other as represented in Fig. 6. The extensions 13 are then bent over to cover the open ends of the tube to form caps therefor, and the projections 14 bent to overlap the end-portions 70 of the tube as clearly represented in Fig. 1, for holding the tube in shape. If desired, the projections 14 and overlapping edges of the tube may be soldered together; and a wooden socket represented at 11^a may 75 be applied to the upper end of the casing 11.

The rod to which the beater-blades hereinafter referred to are attached is represented at 15 and is formed with a spiral section 16 intermediate its ends, this rod being preferably formed from a strip of metal 80 spirally twisted to produce the section 16. The opposite ends of the rod 15 are preferably straight as represented at 17 and 18 respectively, the upper section 17 of the rod 85 being provided at its lower end with a shoulder 19 and the lower section 18 containing in its upper end notches 20.

The rod 15 extends at its spiral section 16 through a rectangular slot 21 in the lower 90 cap 13 and is normally held in the extended position illustrated in Figs. 1 and 5, in which barbs 22 cut from the spiral section 16 bear against the upper surface of the lower cap, by a coiled spring 23 in the casing 11, the 95 spring bearing at one end against the under side of the upper cap 13 and at its opposite end against a cup-shaped follower 24 carried by the section 17 of the rod and seated upon the shoulder 19.

The beater-blades, of a form especially adapted for beating eggs, are represented at 25 and 26 and are preferably in the form of spring-metal split bands, the band 25 containing two openings 27 adjacent to its free 105 end-portions, and a single opening 27^a approximately diametrically opposed thereto, these openings which are elongated extend-

ing transversely of the periphery of the band. The band 26 contains openings 28 and 29 located in the same relative positions as the openings 27 and 27^a, the openings in 5 the bands 25 and 26 extending at right- angles to each other.

The bands 25 and 26 are secured to the rod 15 by first inserting one band into the other to cause them to extend at right- 10 angles to each other. They are then contracted, as by squeezing them together, to bring the openings 27 and 28 into alinement with each other, and the end 18 of the rod 15 then inserted through these alining open- 15 ings and the openings 27^a and 29 to the position illustrated in Fig. 10 in which the walls of the openings in the upper portions of the bands spring into engagement with the under-cut walls of the notches 20, whereby the 20 bands are firmly locked upon the rod 15 as illustrated in Figs. 7 and 10.

In operation, downward pressure on the handle 11 when the lower end of the rod 15 bears against the bottom of the receptacle 25 containing the material to be whipped, causes the handle to move down on this rod against the resistance of the spring 23, with the result of rotating the rod and the blades in one direction by reason of the engagement 30 of the spiral with the walls of the opening 21. As soon as the operator relieves the pressure on the handle, the recoil of the spring causes the handle to rise, with the result of turning the rod and beater-blades 35 in the opposite direction. It will thus be understood that by alternately pressing down upon the handle 11, thereby rotating the rod and the blades and compressing the spring, and relieving the pressure on the 40 handle, thus permitting the spring to recoil and raise the handle, the rod and blades will be caused to rotate first in one direction and then in another, thereby thoroughly agitating the material to be whipped.

45 Referring to Figs. 11, 12 and 13, the construction therein shown is the same as that illustrated in the preceding figures, excepting in the following particulars: The rod 15 contains, in addition to the notches 20, a 50 notch 30 in a flat side thereof, and instead of providing barbs 22 on the rod 14 for limiting the outward movement of this rod in the casing 11, a tube 31 is provided for this purpose, which surrounds the upper 55 end of the spiral section 16 of the rod and is located between the lower one of the caps 13 and the follower 24. The rod 15 in this construction is illustrated as equipped with a beater-blade 32 in the form of a disk having strap-sections 33 provided therein, these 60 strap-sections and the adjacent portions of the disk 32 being deflected in opposite directions as represented in Figs. 11 and 13 to permit of the insertion through these straps 65 of the lower end of the rod 15, the upper one

of the straps 33, when the disk 32 is positioned on the rod 15 for use as illustrated in Fig. 11, springing into the notch 30 for releasably holding this disk in place on the rod. The disk 32 is perforated, preferably, 70 by providing openings, such as those shown at 34, in Fig. 11, with wings 35 at the vertical edges of these openings.

In Figs. 14 and 15 I have illustrated a desirable construction of blade for beating bat- 75 ter. This blade, which is designed to be releasably secured to the rod 15, and which is represented at 36, is in the form of a perforated disk provided with strap-sections 37 cut from the metal of the disk and bent 80 to extend out of the plane of the latter. The disk 36 is adapted to be applied to the rod 15 by inserting the lower end of this rod through the strap-sections 37, the upper one of these strap-sections springing into the 85 notch 30 when this disk is positioned on the rod for use.

It will be noted from the foregoing that the different forms of beater-blades illustrated are interchangeable, and that they 90 may be readily applied to and removed from the rod 15 as substitution of one for the other is desired. Thus, a beater constructed in accordance with my invention may be supplied to the user with a set of blades 95 suitable for beating different materials, and the application of any one of the blades to the rod 15 may be quickly and easily effected.

It will be manifest that a beater con- 100 structed in accordance with my invention may be furnished to the user at relatively low cost, as the construction is very simple. Furthermore, and as another item in the matter of the cost of manufacture, it will be 105 observed that the parts of the construction do not require soldering.

What I claim as new, and desire to secure by Letters Patent, is:

1. A device of the character described, 110 comprising a casing, a beater-equipped rod extending at one end into said casing and formed with a spiral section reaching short of its inner end, means on the casing engag- 115 ing with the spiral section of the rod for rotating it when the casing is moved length- wise thereof, a shoulder on said rod adjacent to the inner end of the spiral, projec- 120 tions on the spiral section of the rod for limiting the outward movement of the latter in the casing, a follower fitting over the inner end of said rod and against the shoulder thereon, and a spring in the casing bearing at one end against said follower and tend- 125 ing to force said rod out of the casing.

2. A device of the character described, comprising a spiral rod containing an out- 130 wardly opening notch and means for rotat- ing it, and a beater-blade of spring metal slipped over the end of said rod and pro-

vided with means extending into the notched portion of the rod when the blade is positioned thereon, for releasably holding it to the latter.

5 3. A device of the character described comprising a notched spiral rod and means for rotating it, and an apertured beater-blade of spring metal slipped over the end of said rod with the latter extending through 10 the aperture in the blade, a wall of the aperture extending into the notched portion of the rod and releasably interlocking the blade with the rod for the purpose set forth.

15 4. A device of the character described, comprising a spiral rod, means for rotating the rod, and a beater-blade carried by said rod and formed of a split band containing openings near its free end-portions and an opening in its diametrically opposed portion, with the openings in the free end-portions of the band registering with each other and through which and the other opening in the band the lower end of said rod extends.

25 5. A device of the character described, comprising a spiral rod and means for rotating it, said rod being notched near one end thereof, and a beater-blade carried by said rod and formed of a split band of flexible material provided in its free end-portions with openings, and in its opposed portion with an opening, the openings in the free end-portions of the band registering with each other and through which and the 30 other of said openings the rod extends, the free end-portions of the band engaging with the notched portion of the rod, for the purpose set forth.

6. A device of the character described, 40 comprising a rod provided with a spiral section and a straight flat section, means engaging with the spiral section of the rod for

rotating it, and beater-blades carried by the rod and formed of a pair of split bands each provided in its free end-portions with slots 45 and in its opposed portion with a single slot, the slots in one of the bands extending lengthwise of the band and the slots in the other of said bands extending at angles thereto, one of said bands fitting within the 50 other, with the slots in the free end-portions of both bands registering and through which registering openings and the other openings in the bands the straight section 55 of the rod extends.

7. A device of the character described, comprising a casing affording a handle formed of a tube having caps at its ends provided with projections which lie against the sides of the tube and overlap the joint 60 of the latter, the lower one of said caps containing an angular opening, a rod formed of a spiral section reaching short of its lower end and containing notches in its lower end-portion, the upper end of said rod 65 extending into said casing with the spiral section thereof extending through said opening in one of the caps, a follower on said rod within the casing, a coiled spring in the casing bearing at one end against the latter and at its opposite end against said follower, and a pair of split bands of spring material containing openings in their free end-portions and in the portions opposed thereto, with the openings in the free portions of the bands registering with each other and the lower portion of the rod extending through the registering openings in the free portions of the band and the other 70 openings therein, for the purpose set forth. 75

EMIL A. CHRISTOPH.
